UNITED STATES PATENT OFFICE

CLIFFORD MERCIER AND FRED DIETRICH, OF LOWELL, MASSACHUSETTS

DETACHABLE SINK STRAINER

Application filed March 10, 1932. Serial No. 598,064.

The present invention relates to a detachable sink strainer.

The principal object of this invention is the provision of a detachable sink strainer, 5 which is so formed that when attached to the usual perforated sink strainer it will effectively exclude sediment and prevent clogging of the sink.

Another object of the invention is the provision of effective yet simple, cheap and novel 10 means for readily and detachably securing the strainer to a sink, basin, bathtub, or the like.

Other objects of the invention will become 15 apparent from the following description, when taken in connection with the accompanying drawing, in which:

Figure 1 is a vertical sectional view taken 20 on the line 1—1 of Figure 2 of one form of the invention;

Figure 2 is a plan view thereof; and

Figure 3 is a vertical sectional view of a 25 modification of the invention.

Referring particularly to the embodiment 30 shown in Figures 1 and 2 of the drawing, the numeral 1 denotes a sink having the customary drain opening 2 into which is fitted the usual perforated sink strainer 3. To prevent sediment and kitchen refuse from 35 clogging the sink, the strainer 8 is applied to the sink by means of the pin 4, which has the hooked end 5 so shaped and formed as to be readily insertable through any one of the perforations 6 in the sink strainer 3. To 40 prevent the hook shaped securing pin from dropping into the drain pipe, a cross pin 7 is mounted through a horizontal opening in the pin 4 and spaced a suitable distance from the hooked end of the pin so as to permit the 45 hooked end to be readily inserted in a perforation 6 of the sink strainer and retain it therein.

The detachable strainer, shown in Figures 1 and 2, comprises a substantially conical or 50 frusto-conical portion 8, having a flat rim 9 of relatively great area adapted to cooperate with and be pressed against the surface of the sink strainer 3 by a compression spring 10 interposed between the top of the strainer and a stop disposed at the upper end

of the strainer attaching pin 4. The conical portion of the strainer and the flanged portion are provided with relatively small perforations 11, which are smaller than the perforations 6 in the sink strainer 3. These 55 relatively small perforations prevent the accumulation of scum and sediment upon the sink strainer to a marked degree and effectively prevent the clogging of the drain.

The upper end or apex portion of the conical strainer is provided with a cylindrical open extension 12, forming a shoulder 13' where it meets the conical portion 8 of the strainer and to which the compression spring 10 is suitably secured, as by soldering, brazing, or welding as indicated at 13. The spring at its upper end has soldered thereto, at 17, a sheet metal member 14 provided with an elliptical slot 15 and laterally extending enlarged portions 16, the latter being adapted 70 to be engaged by the fingers of the user to push against and depress the said member in order to compress the coil spring 10, when attaching the strainer to the sink. The coil spring is retained in compression by the cross 75 pin 18 on the main pin 4, which serves as an abutment or stop for the member 14.

To attach the strainer, the pin 4 is inserted with the hooked end within a perforation 6 in the sink strainer 3, as shown in Figure 1. 80 After the pin has been inserted and arranged vertically, the conical strainer is inserted over the pin; the finger piece or member 14 is arranged with the elliptical opening 15 in alignment with the abutment or stop pin 14; the member 14 is then depressed below the stop pin 18 and given a quarter turn so that the elliptical opening 15 is out of registration with the stop pin, as shown in Figure 2. When thus mounted, it is evident that the 85 structure described becomes a rigid whole for the reason that the spring 10 forces the pin 4 upwardly and maintains the hooked end 5 securely against the under face of the sink strainer 3.

When the conical strainer has become clogged and it is desired to permit the outflow of the liquid contents of the sink, the strainer is raised slightly from its seat by lifting it against the spring 10, which will 100

permit the contents to drain out between the strainer flange or rim 9 and the perforated sink strainer 3.

Figure 3 shows a modification of the invention

- 5 which is provided with a different means for securing the strainer in a sink. In this modification, the perforated conical strainer 18' is provided with a relatively wide rimmed perforated flat flange 19, the size of the per-
10 forations 20 in the conical and rim portions of the strainer being considerably smaller than the perforations 21 in the sink strainer 30. As in the form of the invention shown in Figure 1, the strainer is secured in place by
15 means of a hook shaped attaching pin 40 having the hooked end 50 inserted through a perforation in the sink strainer and provided with the stop pin 70 to prevent the hooked attaching pin from dropping into the drain pipe. The upper end of the attaching pin ex-
20 tends slidably through a collar 22 secured within the apex opening 23 of the conical strainer. The collar is preferably formed with a bell mouth or flared opening 24 to
25 facilitate the insertion of the attaching pin within the collar, and a threaded opening 25 is formed in the side of the collar for the reception of a winged set screw 26 for securely retaining the strainer seated in the sink.
30 To drain the sink when the conical strainer has become clogged, the set screw 26 is loos-
35 ened and the strainer raised a sufficient height to permit the liquid contents of the sink to drain out between the flanged portion 19 and its seat on the sink strainer.

While the strainer shown and described herein may be made of any suitable metal, such as, copper, aluminum, or the like, we preferably use dipped tin.

40 It will also be understood that our strainer may be fabricated out of several distinct portions, which are later assembled, as by soldering, brazing, or welding, and that it may also be made by stamping out of unitary sheet metal blanks.

45 It is clear, therefore, that the above described forms of the invention are intended to be merely illustrative of the objects of the invention, and it will be understood that a variety of different modifications are intended to come within the terms of the following claims:

What we claim is:

50 1. An auxiliary strainer for kitchen sinks, comprising a rigid pin adapted to be mounted on a sink strainer, said pin having a smooth shank, an auxiliary strainer element slidable along said pin, and cooperating means be-
55 tween said auxiliary strainer and smooth shank for mounting said auxiliary strainer element on said pin and dismounting it therefrom while the pin remains in place on the sink strainer.

60 2. In combination with a perforated sink strainer, a pin having a smooth shank, means

for securing said pin on said strainer and substantially preventing movement thereof along two opposite vertical directions, a second strainer slidable along said pin and normally adapted to overlie said sink strainer, 7^c and cooperating means between said auxiliary strainer and smooth shank for mounting said second strainer on said pin and dismounting it therefrom.

3. In combination with a sink strainer, a 75 perforated centrally bulged strainer having a relatively wide flat rim adapted to rest against said sink strainer, a hook shaped attaching pin having the hooked end thereof engageable with the sink strainer, and having the other end of said pin extending through the apex of the bulged portion of the strainer, abutment means, a spring confined between said abutment means and the apex portion of the bulged strainer, and quick detachable means between said abutment and said pin, whereby the strainer may be slipped over the last mentioned end of the pin while the pin remains engaged with the sink strainer. 90

4. In combination with a sink strainer, a second strainer having a relatively wide flat rim adapted to rest against said sink strainer, an attaching pin detachably engageable with the sink strainer and extending through said second strainer, a spring abutting at one end the second strainer, and a stop member for the other end of the spring removably secured to the pin, whereby the second strainer may be removed from said pin while the latter is attached to the sink strainer. 95

5. In combination with a sink strainer, a substantially conical shaped perforated strainer having a perforated relatively wide flat rim adapted to rest against said sink strainer, a smooth hook shaped attaching pin having the hooked end thereof detachably engageable with the sink strainer, and having the other end thereof extending slidably through the apex portion of the conical strainer, and means carried by said conical strainer for adjusting the conical strainer longitudinally of the said smooth pin and maintaining it in each position. 110

6. In combination with a perforated sink 115 strainer, a substantially conical shaped perforated strainer having a perforated relatively wide flat rim adapted to rest against said sink strainer, a hook shaped attaching pin having the hooked end thereof engageable with the sink strainer through a perforation thereof, and having the other end of said pin extending through the apex of the conical strainer, a spring abutting at one end the apex portion of the conical strainer, and a stop member removably secured to the pin, whereby the conical strainer may be removed from said pin while the latter is in operable engagement with the sink strainer. 125

7. In combination with a perforated sink 130

strainer, a pin mounted on said strainer, a second strainer slidably mounted on said pin, a bushing secured to said second strainer, said bushing having a tapered central opening for insertion over said pin, and means carried by said bushing for fastening said strainer on said pin.

5 In testimony whereof they hereunto affix their signatures.
